UNITED STATES PATENT OFFICE.

EDUARD UHTHOFF, OF BERLIN-CHARLOTTENBURG, GERMANY.

TYPE-LINE SETTING AND CASTING MACHINE.

Application filed May 27, 1926, Serial No. 112,133, and in Germany August 17, 1925.

The invention relates to type line setting and casting machines in which the matrices move on endless wires. In machines of this type feeding members move matrix bars along a path leading to the magazine and return immediately to their initial position to collect a fresh number of matrix bars which have occupied casting position in the meantime. The constructional problems involved in correctly moving the feeding members are particularly difficult because the matrix bars must be moved substantially along a semi-circle and simultaneously raised so that they may enter the magazine.

The present invention solves the problems involved by providing two sets of such members, after referred to as pushers or push fingers, are reciprocated about a stationary spindle through 180°. These pushers move forward with the collected cast matrix bars and deliver them to the second set, hereinafter referred to as the drivers. The latter are linearly reciprocated. Both sets however when covering their return journey are moved at a suitable point out of the path they follow on their outward or working travel for the purpose of escaping the matrix bars fed in position for further delivery. At the end of the return or idle journey the pushers and drivers move into their working path and are then behind the next group of matrix bars to be moved along.

A construction of the device according to this invention is illustrated in the accompanying drawings in which:

Figures 1 and 2 illustrate two positions of angularly moving pushers;

Figure 3 is a horizontal section on line 3—3 of Figure 1 showing the pushers and drivers in plan;

Figures 4 to 6 show on a larger scale three positions of the connection mechanism between a vertical spindle and the pushers;

Figure 7 is a section along line 7—7 of Figure 4;

Figure 8 is a section on line 8—8 of Figure 4, and

Figures 9 and 10 are sections on line 9—9 of Figure 1, the drivers being shown in two positions.

Matrix bars 1 are moved on superposed guiding wires, three of which are shown in

the construction illustrated. As shown in Figure 3, these wires form a closed or endless path. After being cast at A, the matrix bars 1 are moved in the direction of the arrow (Figure 3) by a rake-like feeder 3 which is not part of the invention. The matrices are then pushed along by push members 5 moving about a vertical spindle 4 while the said matrices simultaneously rise and reach the position shown in Figure 2 from that shown in Figure 1. The set of matrix bars is now engaged by drivers 6 reciprocated along a straight path and rises further until it reaches the highest point, for example B in Figure 3. At this point the matrix bars are distributed over the magazine (not shown).

The vertical spindle 4 is angularly reciprocated through 180° in a suitable way by the actuating mechanism of the machine. A rod 9 carrying the push fingers 5 is connected to the said spindle by links 7, 8, the lower end of the said rod resting on a helical slideway 10 the pitch of which is that of the guiding wires 2. The push members 5 therefore rise from the position of Figure 1 into that of Figure 2 together with the matrix bars.

The spindle 4 is rigidly connected to a guide member having two oppositely disposed guide plates 11, 12 (Figure 8) between which two flat rods 13, 14 are guided which are adapted to move parallel to the longitudinal axis of the spindle 4. The links 7 and 8 are connected to these flat rods 13, 14 through the medium of supports 15 and 16. The upper end of a helical spring 17 surrounding the spindle 4 bears from below on the flat rods 13 and 14 or on the support 15, the lower end of the spring being in contact with a cone member 18 movably mounted on the spindle 4. A slide 20, movable longitudinally on the spindle 4 and partaking in the rotation thereof, is located under the cone member 18 and is guided by a sleeve 19 not connected to the said cone member 18. The arms 21 supporting the link 7 are pivoted on the said slide which moreover carries a bracket 22 suitably engaged by the lower end of a spring catch 24 pivoted at 23, the upper end of the said catch being adapted to engage the guide plate 11 from below. The guide plate 12 carries a spring catch 26 pivoted at 25 and having a

projection 27, the said catch co-operating with a cam 28 secured to the frame of the machine.

The device works as follows:

- 5 The spindle 4 is turned through 180° by the mechanism of the machine as soon as the push fingers 5 engage behind the matrix bars fed from the setting point A (Figures 1 and 4), the rod 9 rising on the slideway 10.
- 10 The links 7, 8 and the arms 21 likewise rise until they reach the position shown in Figures 2 and 5. The rod 9 has thus moved along the path C on the slideway 10. (Figure 3.) The slide 20 together with the 15 sleeve 19 and the cone member 18 are moved upwardly on the spindle 4 by the arms 21 so that the spring 17 is compressed. Compression of the spring is possible owing to the circumstance that at the beginning of 20 the angular motion the catch 24 springs under the guide plate 11 to prevent the support 15 from being pushed upwards, together with the flat rods 13, 14, by the spring 17 under compression. When the 25 rod 9 reaches its highest position the projection 27 of the catch 26 springs into engagement under the cone member 18 and firmly holds the lower end of the compressed spring in position.
- 30 After the matrix bars thus pushed along are delivered to the drivers 6 the spindle 4 turns in the opposite direction, the rod 9 with the pushers 5 moving first along the path C towards the end of which the said 35 rod moves along the path D. This change of travel is essential, as otherwise the push fingers 5 would impinge against the foremost matrix bar of the batch of such bars fed in the meantime from the setting point 40 A, whereas the said fingers should engage behind the rearmost bar. The rod 9 is moved out of the path C by releasing the catch 24, and through the medium of the locking gear 18, 27. The lower end of the 45 compressed spring 17 is held in the raised position by the said gear while the now released catch 24 allows the upper end of the spring to move upwards. While the push fingers 5 are returning to their initial position the slide 20 glides downwards on the spindle 4; towards the end of this movement the bracket 22 presses on the tapering lower end of the catch 24 to move the latter clear of the guide plate 11. The upper end 50 of the compressed spring 17 can now rise (Figure 6) so that the rod 9 moves into the path D and occupies a position 29 shown in dotted lines in Figure 1. At this moment the cam 28 releases the catch 26 so that the 55 spring 17 expands downwardly and the flat rods 13 and 14 drop by gravity together with the support 15, the rod 9 being moved along a straight line on the path E (Figure 3). The push fingers 5 are now in a position 60 in which they engage behind the rear-

most matrix bar of the set of such bars fed in the meantime from the setting point A, so that the said fingers may now again move forward.

When the matrix bars are pushed forward 70 by the angularly moving fingers 5 steps must be taken to prevent the matrix bars from colliding with the returning drivers 6. To this end the said drivers are moved out of the path of the matrix bars. These driving fingers 6 are guided on a straight rail 30 (Figures 3, 9 and 10) pivoted about a point 31 at the rear of the frame of the machine. The front end of this rail has a stem 32 axially movable on the frame 33 of the machine, and constantly urged by a spring 34 to lie parallel to the guiding wires 2. A cam disc 35 is mounted on the spindle 4 and presses against a tappet 36 guided along a straight line. A double-armed lever 38 is pivoted at 37 on the said tappet, one end of the said lever bearing against a plate 39 carried on the stem 32. The spindle 4 carries a spur 40 adapted to press against the lever 38.

While the pushers 5 are moving forward the cam disc 35 pushes the tappet 36 forward so that with the aid of the lever 38 the stem 32 is moved out of the position of Figure 9 or Figure 3 (shown in full lines) 95 into the position of Figure 10 (shown in dotted lines in Figure 3). At the same time a spring 41 pulls the lever 38 so that its front end impinges against the plate 39, and the drivers 6 are moved out of the path of the matrix bars. As soon as the push fingers 5 reach their forward outermost point, the spur 40 presses on the lever 38 and moves it clear of the plate 39, with the consequence that the drivers 6 are moved by the spring 34 into the path of the matrix bars and engage behind the rearmost bar. 100

The spring 42 then moves the tappet 36 back to its initial position the front end of the lever thus impinging again against the 110 plate 39.

The drivers 6 are reciprocated in the usual manner on the rail 30 through the medium of an endless chain 42 and a chain wheel 43 suitably rotated by the mechanism of the 115 machine.

I claim:

1. In a type line setting and casting machine, matrices guided on endless wires, means reciprocating in a curve and moving 120 the matrices from the setting place on curved parts of said endless wires and means reciprocating along the straight parts of said wires and moving the matrices from the curved parts of said wires to the magazine. 125

2. In a type line setting and casting machine, matrices guided on endless wires, a set of push fingers reciprocating in a curve and moving the matrices from the setting place on the curved parts of said wires, an- 130

other set of push fingers reciprocating along the straight parts of said wires and moving the matrices from the curved parts of said wires to the magazine, means to move both 5 the sets of push fingers during their return travel out of the path of the matrices and means to return said sets of push fingers.

3. In a type line setting and casting machine, matrices guided on endless wires, a spindle, links pivotally connected to said spindle, a rod pivotally carried by said links, push fingers on said rod, a slideway rising according to the rising of the wires and guiding said rod and means reciprocating along the straight parts of said wires and moving the matrices from the curved parts of said wires.

4. In a type line setting and casting machine, matrices guided on endless wires, a reciprocating spindle, links pivotally connected to said spindle, a rod pivotally carried by said links, push fingers on said rod, a slideway rising according to the rising of the wires and guiding said rod, reciprocating push fingers to move the matrices to the magazine, means to move both the sets of push fingers during their return travel out of the path of the matrices, means to return said sets of push fingers at the end of their return travel back again to the path of the matrices.

5. In a type line setting and casting machine, matrices guided on endless wires, a reciprocating spindle, links pivotally connected to said spindle, a rod pivotally carried by said links, push fingers on said rod, a rising slideway guiding said rod, a spring carried by said spindle and supporting said links, means to compress said spring when raising the rod, means to lock said compressed spring, means to release the upper end of said spring when the rod sinks, means to release the lower end of said spring when one entire reciprocating movement of the spindle is finished and means reciprocating along the straight parts of said wires and moving the matrices from the curved parts of said wires to the magazine.

50 6. In a type line setting and casting machine, matrices guided on endless wires, a reciprocating spindle, vertically sliding members on said spindle, links pivotally connected to said members, a rod pivotally carried by said links, push fingers on said rod, a rising slideway guiding said rod, a spring on said spindle supporting said sliding members, means to compress said spring when raising the rod, means to lock said sliding members when compressing said spring, means to lock the lower end of said spring when the rod sinks, means to release said spring lock when one entire reciprocating movement of the spindle is finished and means reciprocating along the straight parts

of said wires and moving the matrices from the curved parts of said wires to the magazine.

7. In a type line setting and casting machine, matrices guided on endless wires, 70 a reciprocating spindle, oppositely disposed guide plates rigidly mounted on said spindle, bars vertically sliding between said guide plates, links pivotally connected to said bars, a rod pivotally carried by said links, push fingers on said rod, a rising slideway guiding said rod, an arm pivotally connected to one of said links, a slide block on said spindle pivotally connected to said arm, a member above said slide block and 75 sliding on said spindle, a spring on said spindle and supporting said sliding bars and compressed by said member, a spring catch engaging said guide plates from below when compressing said spring and released during 80 the return movement of the spindle, means to lock the lower end of said spring when the rod sinks, means to release said spring lock when one entire reciprocating movement of the spindle is finished and means 85 reciprocating along the straight parts of said wires and moving the matrices from the curved parts of said wires to the magazine.

8. In a type line setting and casting machine, matrices guided on endless wires, a reciprocating spindle, guide plates oppositely disposed and rigidly mounted on said spindle, bars vertically sliding between said guide plates, links pivotally connected to said bars, a rod pivotally carried by said links, push fingers on said rod, a rising slideway guiding said rod, an arm pivotally connected to one of said links, a slide block on said spindle pivotally connected to said arm, a bracket on said slide block, a cone member above said slide block sliding on said spindle, a spring carried by said spindle and supporting said sliding bars and compressed by said slide block, a spring catch pivoted to said sliding bars and engaging said guide plates from below when compressing said spring and released by said bracket when the said spindle is returned, another spring catch pivoted to said guide plates, a projection on said second spring catch engaging said cone member from below, when the spring is compressed, a cam releasing said second spring catch when the return movement of said spindle is completed and means reciprocating along the straight parts of said wires and moving the matrices from the curved parts of said wires to the magazine.

9. In a type line setting and casting machine, matrices guided on endless wires, a set of push fingers reciprocating in a curve and moving the matrices from the setting place on the curved parts of the said endless wires, means to move said set of push 130

5 fingers during their return travel out of the path of the matrices, means to return said set of push fingers at the end of their return travel back again to the path of the 10 5 matrices, a second set of push fingers reciprocating along the straight part of the wires guiding the matrices to the magazine, a rail guiding said second set of push fingers and pivotally mounted at its rear end, means to 15 push said rail with the push fingers out of the path of the matrices during the return travel of said push fingers, means to move said rail with the push fingers at the end of their return travel back again into the 20 path of the matrices.

10. In a type line setting and casting machine, matrices guided on endless wires, a set of push fingers reciprocating in a curve and moving the matrices from the setting 20 place on the curved parts of the wires, means to move said set of push fingers during their return travel out of the path of the matrices, means to return said set of push fingers at the end of their return travel back 25 again to the path of the matrices, a second set of push fingers reciprocating along the straight part of the wires guiding the matrices to the magazine, a rail guiding said second set of push fingers and pivot- 30 ally mounted at its rear end, a rotating spindle, a cam disc on said spindle, a tappet pushed by said cam disc, a lever pivoted on said tappet, a plate pushed by said lever, a sliding stem carrying the said rail and connected with said plate, a spur on said spindle moving the said lever clear of the said plate, a spring to draw the said rail back into its initial position, another spring 35

drawing back the said tappet, a third spring swinging the said lever into impingement 40 with the said plate.

11. In a type line setting and casting machine, matrices guided on endless wires, a reciprocating spindle, guide plates oppositely disposed and rigidly mounted on said spindle, bars vertically sliding between said guide plates, links pivotally connected to said bars, a rod pivotally carried by said links, push fingers on said rod, a rising slide-way guiding said rod, an arm pivoted to one of said links, a slide block on said spindle and pivotally connected to said arm, a bracket on said slide block, a cone member above said slide block and sliding on said spindle, a spring on said spindle and supporting said 55 sliding bars and compressed by said slide block, a spring catch pivoted to said sliding bars and engaging said guide plates from below when compressing said spring and released by said bracket when returning the 60 said spindle, another spring catch pivoted to said guide plates, a projection on said second spring catch engaging said cone member from below when the spring is compressed, a cam releasing said second spring catch 65 when the return movement of said spindle is completed, a second set of push fingers reciprocating along the straight part of the wires guiding the matrices to the magazine, a rail guiding said second set of push 70 fingers and pivotally mounted at its rear end and means to swing the rail out of and into the path of matrices.

In testimony whereof I affix my signature.

EDUARD UHTHOFF.
